SLIP ELEVATOR

Chester Albert Lundeen, Los Angeles, Calif., assignor to Byron-Jackson Co., Los Angeles, Calif., a corporation of Delaware

Application January 13, 1936, Serial No. 58,907

6 Claims. (Cl. 24—263)

This invention relates to slip elevators for raising and lowering strings of pipe or rod in wells and has to do particularly, although not exclusively, with structural details for satisfying 5 special requirements in large elevators for handling very large pipe or casing.

An object of the invention is to provide a particularly effective mechanism for automatically raising the slips of a slip elevator in response 10 to opening movement of the elevator.

Another object is to reduce the force required to open a slip elevator of the type in which the slips are raised in response to opening of the elevator.

15 Another object is to provide a slip type elevator for handling very large pipe, which elevator is not of ungainly dimensions and weight while at the same time having ample strength to support heavy strings of pipe or casing.

20 Another object is to provide a lock for the latch of a slip type elevator, which lock can be adjusted to be self-locking when the elevator is supporting a pipe or can be adjusted to be non-self-locking if the additional safety of a self-locking latch is 25 not required or desired.

Another object is to provide an elevator construction in which the links for supporting the elevator are positively retained in engagement 30 with the link-engaging elements on the elevator and in which the strength of the link-engaging members is increased without materially increasing the size or weight.

Briefly, an elevator in accordance with my construction comprises a pair of body members 35 hingedly connected together and adapted to be

swung together or apart to engage or release a pipe, as the case may be. The body members are provided with slips mounted on inclined seats so that when the slips are in lowermost position 40 with the elevator closed they grip a pipe. In order to position the elevator about a pipe to close and lock it, however, the slips must be in uppermost position, out of engagement with the pipe. In accordance with my invention, I automatically

45 elevate the slips in response to opening movement of the elevator by providing a cam on each body member adjacent the hinge, the cams being so arranged that the cam on each body member engages a slip on the other body member and 50 elevates it in response to opening movement of the elevator.

In large elevators the slips may be quite heavy and might impose considerable resistance to the opening of the elevator. To reduce this resistance I prefer to partly support the weight of each

slip by a spring. The springs, however, must not be capable of supporting the entire weight of the slips else the latter would not set themselves.

Heretofore, to the best of my knowledge, it has been universal practice to support elevators on 5 links which engage ears or trunnions extending laterally from opposite sides of the elevator. With this construction the points of support are spaced outwardly a substantial distance from the periphery of the pipe engaged by the elevator. As 10 a result, there is a twisting or turning strain imposed upon the elevator tending to spread it at the bottom and compress it at the top. In order to resist these spreading and compressing forces, the elevator body must be made relatively heavy. 15 In large elevators for handling very large pipe or casing the weight and the lateral dimensions of the elevator may become prohibitively great. In accordance with the present invention, I reduce the weight and the lateral dimensions 20 of an elevator by mounting the link-engaging members on the upper end of the elevator closely adjacent the pipe-opening in the elevator instead of employing trunnions extending laterally from the elevator. My construction places the points 25 of support of the elevator closely adjacent the pipe and greatly reduces the twisting strain on the elevator body, thereby making possible a substantial reduction in the size and weight of the body members. Furthermore, the link-engaging 30 members, being placed directly above the elevator, need not extend out an appreciable distance beyond the periphery of a pipe in the elevator, thereby reducing the space required for the elevator.

35 The exact manner in which all of the aforementioned objects may be achieved will be explained in detail with reference to the drawings which illustrates the invention as embodied in a side door elevator. It is to be understood, however, that various features of the invention may be employed in center latch elevators as well as side door elevators and that the invention is not limited to the latter type.

In the drawings:

Fig. 1 is a perspective view of a side door elevator in accordance with the invention, shown in fully open position;

Fig. 2 is a plan view of the elevator, with parts broken away to show details of construction, with 50 the elevator in closed position;

Fig. 3 is a front elevation of the elevator in closed position, a portion of the elevator being broken away and shown partly in section to better illustrate the construction employed;

45

55

Fig. 4 is a detail section view illustrating the latch for maintaining the slips in retracted position, the view being taken in the plane IV—IV of Fig. 2 and showing the slip retained in retracted position;

Fig. 5 is a view similar to Fig. 4, showing the slip released;

Fig. 6 is a detail sectional view taken in the plane VI—VI of Fig. 2, showing the manner in which the slips are mounted and partly supported by springs; and

Fig. 7 is a detail horizontal sectional view showing the construction of the adjustable lock on the door latch of the elevator.

Referring to Figs. 1, 2 and 3, the side door slip elevator therein depicted comprises a main body member 1 having hingedly connected thereto at one end a door 2. Thus the body member 1 is provided with hinge lugs or eyes 3 and 4, respectively, the door 2 is provided with hinge lugs 5 and 6, respectively, and a hinge pin 7 extends through the lugs 3, 4, 5 and 6 to pivotally connect them together.

The body member 1 is also provided with link-engaging ears or hooks 10, both of which are identical with each other and are positioned diametrically opposite each other on opposite ends of the body member 1. As is most clearly shown in Fig. 3, these members 10 rise directly out of the upper end or edge of the body member 1 so that they will be positioned relatively close to a pipe supported by the elevator. Each of the members 10 comprises a relatively heavy arm formed integrally with the body member 1 and comprising a vertical portion 11 rising out of the body member 1 and merging into an outwardly and downwardly curved hook portion 12 having a curved seat 13 on its under surface for contacting lifting links 14 (shown in broken lines in Fig. 3).

To provide support for the outer end of each member 10 and to prevent escape of the link 14 from the seat 13, a latch 15 is provided which is pivotally attached by a pin 16 to the outer end of the arm portion 12 and is adapted to swing between an open position (shown in dotted lines in Fig. 3) and a closed position (shown in full lines in Fig. 3). To facilitate the mounting of the latch 15, the outer end of the arm 12 is preferably bifurcated, as shown in Fig. 2, thereby providing two walls between which the latch 15 is positioned. The slot or passage between the bifurcated ends of the portion 12 extends inwardly past the seat 13, as shown in Fig. 3, for receiving a short arm 17 on the latch 15.

When the latch 15 is in fully open position, as shown in dotted lines in Fig. 3, the arm 17 extends downwardly across the opening through which the link 14 must pass to reach the seat 13. When the latch 15 is in fully closed position, as shown in full lines in Fig. 3, the lower edge of the arm 17 is substantially flush with the seat 13. A spring catch 18 is provided for releasably retaining the latch 15 either in open or closed position, the latch being oscillatable about a supporting pin 19 and having a shoulder 20 adapted to engage against shoulders 22 and 23 on the latch 15. The catch 18 may be manually released by pressing it inwardly against the tension of the spring 24. However, it is purposely designed as shown to have no outwardly projecting parts which might be accidentally engaged.

When the links 14 are to be placed in seating position, the latches 15 are lifted into open position in which position they are retained by the

catch 18. The links 14 are then pressed against the arm 17 which rotates the latches 15 into the closed position (the shoulders 20 and 22 being slightly rounded to permit release of the latch 15 in response to substantial pressure against the arm 17). Then when lifting force is applied to links 14 the latter pull up tight against the seats 13 and positively prevent the latches 15 from opening. Each latch 15 is provided at its lower end with a pair of laterally projecting lugs 26 having arcuate bearing surfaces 27 which slip over and engage complementary surfaces 28 on the body member 1. With this construction as soon as sufficient tension is applied to the links 14 to flex the link-engaging members 10 the faces 27 on the lugs 26 seat tightly against the faces 28 on the body member so that further strain is distributed between the portion 11 of the member 10 and the latch 15. This provides support on both sides of each of the seats 13 and makes it possible to make the portion 11 of lighter construction than would be necessary if the link 15 did not provide reinforcement as described.

When a link 14 is to be removed from seating engagement with the catch 15, the catch is depressed to disengage the shoulder 23 on the latch 15 and the link is pulled straight out, thereby swinging the latch 15 into open position as shown in dotted lines.

Both the body member 1 and the door 2 are provided with a pair of slips 30 and 31, and 32 and 33, respectively, for engaging a pipe with which the elevator is to be used. The body member 1 and the door 2 are each provided with inwardly and downwardly tapered seats for slidably supporting the slips, the general shape of the slip seats being shown in Figs. 4 and 5. Thus it will be observed that the slip seats are stepped to provide two vertically spaced surfaces 34 and 35, respectively, and the slips are similarly stepped to correspond. To retain the slips in position on their seats a pin 36 (Fig. 6) is provided for each slip, these pins extending through holes drilled therefor in the body member 1 or the door 2, as the case may be, and also through holes provided therefor in rearwardly extending lugs 37 and 38 on each slip. The central portion of each slip seat is recessed as indicated at 39 to provide room for the lugs 37 and 38. Pins 36 may be of reduced diameter at their lower ends, as indicated at 40, to fit in relatively small holes 41 provided therefor in the body member or door, as the case may be. By reason of the small end 40 a shoulder 40a is provided on each pin which rests against the edges of the holes 41 and prevents downward escape of the pin 36. The pins may be prevented from escaping upwardly out of the body member or door, as the case may be, by screw plugs 42.

As previously indicated, in very large size elevators the weight of the slips may be so great as to make it difficult to raise them into retracted position and it may be desirable in such instances to provide springs for partly supporting the weight of the slips. In the construction disclosed in Fig. 6, the spring means employed may be a helical spring 43 positioned about the pin 36 and compressed between the body member surrounding the hole 41 and the lug 38 on the slip.

To automatically raise the slips into retracted position in response to opening of the elevator, I provide a cam 45 on the hinge eye 3 secured to the body member 1 and a cam 46 on the hinge eye 5 secured to the door 2, these cams being

provided with cam surfaces 47 extending helically in opposite directions about the hinge pin 7. The surface 47 on the cam 45 engages a shoulder 48 on the slip 31 in the door 2 so that when the door 5 is opened the slip 31 is forced to ride upwardly along the cam 45. Likewise the slip 32 in the body member 1 is provided with a shoulder 48 which bears against the surface 47 of the cam 46 so that in response to opening movement of the 10 door 2 slip 32 rides upwardly along the cam 46. To force all of the slips to move upwardly in unison with the slips 31 and 32, the slips 30 and 31 are interengaged by a tongue and groove connection and likewise the slips 32 and 33 are interengaged by a tongue and groove structure. These 15 structures are shown in Figs. 2 and 3 of the drawings. Thus the slip 33 is provided with a tongue 50 engaging in a recess 51 in the edge of slip 32 and the slip 31 is provided with a tongue 52, 20 which engages in a recess 53 in the slip 30.

When slip 30 has been moved into uppermost position in response to opening movement of the elevator, it is retained in that position by a latch to be described later. Therefore, when the elevator 25 is again closed the slip 30 remains in uppermost position until the latch retaining it is tripped. The slip 31 is likewise retained in uppermost position because of the engagement of the tongue 52 on slip 31 with the recess 53 in slip 30. 30 Slip 32 is likewise supported in uppermost position by slip 31 through an arcuate finger or arm 55 (Fig. 1) on the slip 31 which engages with a shoulder 56 on the slip 32 in all positions of the door 2. Slip 33 is in turn supported in uppermost 35 position from slip 32 because of the tongue 50 and the cooperating groove 51.

The latch mechanism for directly supporting the slip 30 in retracted position will now be described with reference to Figs. 2, 4 and 5. It 40 comprises a housing member 60 formed integrally with and extending upwardly from the top of the door 2 an appreciable distance. This housing member 60 has a slot-shaped recess in the upper end, in which the bifurcated upper end of a link 61 is positioned, for vertical sliding movement. The lower end of the link 61 is attached to the upper end of the slip 30 so that the link 61 and the slip 30 are forced to move upwardly and downwardly in unison (as shown in the drawings, 45 the link 61 is formed integrally with the slip 30). A pin 64 extends through the bifurcated upper ends of the link 61 and through a journal provided therefor in a latch member 65 supporting the latter for rotary motion with respect to the link 61. The latch member 65 is constantly urged 50 into the position shown in Fig. 4 by a helical spring 66, which is positioned in an arcuate slot 67 in the latch and is compressed between one end wall 68 of the recess 67 and a pin 69 anchored to the link 61. The latch 65 is provided 55 with an arm 70 which extends almost but not quite into contact with a pipe positioned within the elevator, this pipe being indicated at 71 in Figs. 4 and 5. The end face 72 of the arm 70 is 60 preferably convexedly curved in a vertical plane concentrically with respect to the pin 64 and is curved concavely in a horizontal plane about the central axis of the elevator so that it conforms approximately to the curvature of the pipe 71. 65 The latch 65 is also provided with an arm 73 having an eye hole 74 therein for the attachment of a line and having a shoulder 75 thereon adapted to rest against a stop member 76 on the housing 60.

To limit rotation of the latch 65 about the

pivot pin 64, a shoulder 77 is also provided on the housing member 60. The housing 60 is also preferably provided with an apron 78 to partially enclose and protect the arm 73 when the latch is in released position.

As shown in Fig. 4, the slips are in retracted position and slip 30 is held in this position by engagement of the shoulder 75 on arm 73 with the shoulder 76 on the housing 60. The remaining slips are supported by virtue of the fact that they 10 are connected to slip 30.

The slips may be released in either of two ways. One way is to pull the arm 73 outwardly (as by a line attached thereto), thereby disengaging the shoulders 75 and 76 and permitting 15 the arm 73 to rotate into engagement with the shoulder 77, as shown in Fig. 5. In this position the link 61 and the slip 30 drop until the slip engages a pipe positioned within the elevator.

The other way of releasing the slips is to move 20 the elevator, after it has been enclosed around a pipe, upwardly along the pipe until the arm 70 at the latch 65 engages the coupling 80 on the upper end of the pipe. Thereafter a slight further upward movement of the elevator rotates the 25 latch 65 about the pin 64 until shoulders 75 on arm 73 disengages the shoulders 76 on the housing whereupon the latch 65 and the link 61 are free to drop with the slip into pipe-setting position, as shown in Fig. 5.

By virtue of their weight, the slips drop very quickly as soon as the shoulder 75 is released from engagement with the shoulder 76, carrying the link 61 and the latch 65 down with them so that the arm 70 drops away from the collar 80 35 on the pipe, thereby preventing undue strain being imposed upon the latch mechanism.

After the pipe has been released and the elevator opened to remove it from the pipe, the slips are elevated automatically in the manner previously described and the upward movement of the slip 30 raises the link 61, permitting the spring 66 to retract the latch 65 into the position shown in Fig. 4 in which the shoulder 75 on arm 73 again engages the shoulder 76 on the housing member 40 60, thereby retaining the slips in retracted position until they are again purposely released.

Of course in any elevator, particularly any slip type elevator in which the slips are wedged between the pipe and the body member and door 50 of the elevator, the door must be positively and rigidly locked in closed position during a pipe lifting operation. Various door latches may be employed in the construction described but a particularly effective one has been illustrated and 55 is shown to best advantage in Figs. 1, 2 and 7. Thus it comprises a latch 90 hingedly connected to one end of the body member 1 by a pin 91 (Fig. 7) and adapted to engage shoulders 92 and 93 on the end of the door 2 when the elevator is 60 in closed position. The latch 90 is preferably provided with a handle 94 to facilitate opening and is constantly urged into locking position by a helical spring 95 compressed between a recessed wing 96 on the latch and the body member 1.

The rear faces of the shoulders 92 and 93 are rounded off as shown in Fig. 1 and the front faces of the latch 90 are likewise rounded off so that when the door 2 is slammed shut the latch 90 is automatically forced outwardly by contact- 70 ing with the rounded faces on the shoulders 93 and 94 to permit the latch to slip thereover. Of course, when the door is fully closed the spring 95 snaps the latch over the shoulders 92 and 93 into the position shown in Fig. 7, in which 75

the rear substantially flat faces 97 of the latch engage against the front faces of the shoulders 92 and 93. The main portions of the front faces of shoulders 92 and 93 are slightly convex and concentric relative to the latch pin 91 when the door is in closed position to facilitate closing and opening of the latch.

However, in some instances it is desired that the latch be positively locked in closed position 10 when the weight of a pipe is on the elevator, the weight of the pipe acting upon the slips of the elevator tending to open the door. To this end, I prefer to form a ridge 99 on the latch engaging face of the shoulder 92, which ridge instead of 15 being rounded off extends substantially straight, as clearly shown in Fig. 7. The latch member 98 is provided with a screw 100 extending therethrough at the level of the ridge 99 on the shoulder 92 so that when its screw 100 is adjusted so 20 that its end extends beyond the face 97 of the latch it contacts the ridge 99, as shown in Fig. 7. The ridge 99 is inclined at such an angle that in order for the latch to open the door must be 25 fully closed. Therefore, if the latch is once closed and the slips set into engagement with a pipe the force of the slips acting between the pipe and the body member 1 and the door 2 tends to open the door, forcing the ridge 99 up against the end of the screw 100 and positively preventing 30 any opening movement of the latch. However, after the slips have been retracted so that the door 2 can move into fully closed position, then the ridge 99 is displaced far enough away from the edge of the screw 100 to permit opening 35 of the latch.

In case it is not desired to utilize the self-locking feature described, the screw 100 is simply turned out until its end is flush with the face 97, whereupon it forms no function in the operation 40 of the latch and the latch may be opened or closed without the door 2 being in fully closed position so long as the opening pressure on the door does not produce sufficient friction between the engaging faces of the latch and the shoulders 45 92 and 93 to prevent movement of the latch.

For purposes of illustration, the various features of my invention have been described as incorporated in a particular side door slip elevator. It will be apparent to those skilled in the art 50 that various modifications may be made in the particular elevator construction illustrated without departing from the spirit of the invention and the invention is therefore to be limited only as set forth in the appended claims.

55 I claim:

1. A slip elevator of the type described comprising a pair of pipe encircling body members, hinge means for pivotally connecting said members for relative swinging movement into closed 60 and open positions, inwardly and downwardly inclined slip seats on said members, slips slidably supported on said slip seats for downward movement therealong into pipe-engaging position and upward movement therealong into retracted positions, and means on each of said body members defining a cam surface adapted to slidably contact a cooperating cam surface on a slip on the other body member, said cam surfaces being so inclined as to lift the slips they slidably contact 65 in response to opening movement of said body members.

2. A slip elevator of the type described comprising a pair of pipe encircling body members, each having hinge eyes thereon and a hinge pin 70 extending through said eyes for hingedly con-

necting said body members together for relative swinging movement into closed and open positions, inwardly and downwardly inclined slip seats on said members, slips slidably supported on said slip seats for downward movement therealong into pipe engaging position and upward movement into retracted position, one at least of the hinge eyes on each of said body members having a cam surface thereon extending helically about the axis of the hinge and adapted to 10 contact a cooperating cam follower surface on a slip on the other body member, the cam surfaces on the hinge eyes on the two body members extending in opposite directions about said hinge pin whereby said slips are lifted in response to 15 opening movement of said body members.

3. A slip elevator of the type described comprising a pair of pipe encircling body members, hinge means for pivotally connecting said members for relative swinging movement into closed 20 and open positions, inwardly and downwardly inclined slip seats on said members, slips slidably supported on said slip seats for downward movement therealong into pipe-engaging position and upward movement therealong into retracted 25 positions, means on each of said body members defining a cam surface adapted to slidably contact a cooperating cam surface on a slip on the other body member, said cam surfaces being so inclined as to lift the slips they slidably contact 30 in response to opening movement of said body members, and latch means for releasably retaining said slips in retracted position during and following closing movement of said body members.

4. A slip elevator of the type described comprising a pair of pipe encircling body members, hinge means for pivotally connecting said members for relative swinging movement into closed 40 and open positions, inwardly and downwardly inclined slip seats on said members, a plurality of slips slidably supported on the slip seats on each of said members for downward movement therealong into pipe-engaging position and upward movement therealong into retracted position, means on each of said body members defining a cam surface adapted to engage a cooperating cam follower surface on one of the slips of the other body member, said cam surfaces being so inclined as to lift the slips they slidably contact 50 in response to opening movement of said body members, and means linking all of the slips on each body member together for simultaneous movement up and down in unison.

5. A slip elevator of the type described comprising a pair of pipe encircling body members, hinge means for pivotally connecting said members for relative swinging movement into closed and open positions, inwardly and downwardly inclined slip seats on said members, slips slidably supported on said slip seats for downward movement therealong into pipe-engaging position and upward movement therealong into retracted positions, means on each of said body members defining a cam surface adapted to slidably contact a cooperating cam surface on a slip on the other body member, said cam surfaces being so inclined as to lift the slips they slidably contact in response to opening movement of said body members, and spring means for urging said slips 70 upwardly into retracted position, said spring means exerting insufficient force to balance the weight of the slips.

6. A slip elevator of the type described comprising a pair of pipe encircling body members, 75

hinge means for pivotally connecting said members for relative swinging movement into closed and open positions, inwardly and downwardly inclined slip seats on said members, slips slidably supported on said slip seats for downward movement therealong into pipe-engaging position and upward movement therealong into retracted positions, means on each of said body members defining a cam surface adapted to slidably contact a cooperating cam surface on a

slip on the other body member, said cam surfaces being so inclined as to lift the slips they slidably contact in response to opening movement of said body members, spring means associated with each of said slips for individually urging each slip upwardly into retracted position, said spring means exerting insufficient force to balance the weight of the slips. 5

CHESTER ALBERT LUNDEEN. 10
